[57] CLAIM

I claim the ornamental design for a medical alert wristwatch, as shown and described.

DESCRIPTION

FIG. 1 is a perspective view of my design;
FIG. 2 is a front view thereof;
FIG. 3 is a back view thereof;
FIG. 4 is left side view thereof, the left and right sides being
symmetric; and,
FIG. 5 is a end view thereof.

1 Claim, 1 Drawing Sheet
